UNITED STATES PATENT OFFICE.

CHARLES E. KNOELLER, OF JERSEY CITY, NEW JERSEY, ASSIGNOR TO JOHN A. SUTHERLAND, OF SAME PLACE.

CLOTHES-DRIER.

SPECIFICATION forming part of Letters Patent No. 487,533, dated December 6, 1892.

Application filed June 4, 1891. Serial No. 395,061. (No model.)

To all whom it may concern:

Be it known that I, CHARLES E. KNOELLER, a citizen of the United States, residing at Jersey City, in the county of Hudson and State of New Jersey, have invented a new and useful Improvement in Clothes-Driers, of which the following is a specification.

Clothes-driers have heretofore been made in which there are movable slats or arms, which, when out of use can be in a nearly-vertical position and rest upon a shelf with their upper portions within a slotted bracket, and these arms can be turned out into a horizontal position when required for use. In this class of clothes-driers a difficulty has been experienced from the slats or arms and the clothes hung upon them being in the way, especially when the drier is employed in a kitchen or other room.

My present invention relates to the combination, with a clothes-drier having movable arms and supporting shelf and bracket, of a stationary rod supported at its upper and lower ends, and metallic clips or straps fastened to the back of the clothes-drier board and surrounding the vertical rod, so that the clothes-drier can be raised or lowered and held by a catch passing through the bottom of the sliding board and into the stationary rod. By this means the board is available as a means for sliding up the clothes-drier slats and the clothes supported by them, so as to be in a sufficiently-elevated position and out of the way, and by the reverse movement the clothes-drier and clothes can be lowered, and when not in use the clothes-drier can be supported in the elevated position and out of the way.

In the drawings, Figure 1 is an elevation of the clothes-drier and its support in a folded condition. Fig. 2 is a vertical section. Fig. 3 is a section in larger size of the vertical rod, portions of the board, and the shelf and bracket. Fig. 4 is a detached view of the bracket. Fig. 5 is a plan view with the board and rod in section. Fig. 6 is an elevation of the shelf, and Fig. 7 is a plan view of the same.

The slats or arms *f* are usually of wood, and in their folded or out-of-use position they rest

at their lower ends upon the semicircular shelf *e*, the edge of which is provided with a rim, and they pass through the slotted bracket *d*, and this bracket *d* and shelf *e* are fastened permanently to the vertical board or back *b*, 55 and when the slats or arms are required for use they are drawn up through the slotted bracket *d* and turned down into a horizontal position, as indicated by dotted lines in Fig. 2, so that their inner ends are held by the bracket *d*. Devices somewhat similar to those have been made and sold on the market. I provide a stationary rod *a*, permanently fastened at its upper and lower ends and of a suitable length, preferably sufficient to extend from the floor to the ceiling, and the supports at the top and bottom ends are blocked out, so that the rod, except at the extreme ends, is kept away from the wall, and the straps and clips 5 are passed around this rod 70 *a* and securely fastened to the back of the board *b*, so that this board *b* is connected with the rod *a*; but it can be slipped freely up or down upon such rod, and the parts are secured in the desired position by a pin or catch 75 *c*, passing through the lower end of the board *b* into one of the holes 2 or 3 in the rod *a*, and it is usually preferable to provide a spring to the catch or pin *c* for holding the same in position, which spring is represented as passing 80 up between the shelf *e* and the back board *b*. By this improvement the clothes-drier when not in use and in the folded condition represented in Figs. 1 and 2 can be pushed up to the ceiling, or nearly so, and there held in position by the pin *c* entering the hole 3, and when required for use the drier can be lowered after the pin *c* has been withdrawn, and such drier can be supported at any convenient height for the clothes to be hung upon 90 the slats or arms when in a horizontal position by the pin passing into either one of the holes 2, and after the clothes-drier has been filled with clothes the drier and clothes can be raised bodily and conveniently by pressing against the lower end of the board *b*, and when properly elevated the drier is held by the catch or pin *c* introduced into the proper hole.

I claim as my invention—

The combination, with a vertical rod *a*, having holes at various places, of a board *b*, straps *5*, passing around the rod *a* and connected to the back of the board near its ends, whereby 5 the board is movable lengthwise on the rod *a*, a spring-catch *c* at the lower end of the board to enter the holes in the rod and support the board at various heights, a bracket

d and shelf *e*, connected to the face of the board *b*, and the movable slats *f*, substantially as set forth.

Signed by me this 1st day of June, 1891.
CHAS. E. KNOELLER.
